F. E. BEST

LOCK FACE

Filed Oct. 9, 1924

Frank Ellin Best.
INVENTOR

UNITED STATES PATENT OFFICE.

FRANK ELLISON BEST, OF SEATTLE, WASHINGTON, ASSIGNOR TO FRANK E. BEST, INC., OF SEATTLE, WASHINGTON, A CORPORATION OF WASHINGTON.

LOCK FACE.

Application filed October 9, 1924. Serial No. 742,599.

To all whom it may concern:

Be it known that I, FRANK ELLISON BEST, a citizen of the United States, residing at Seattle, county of King, and State of Washington, have invented a new and useful Lock Face, of which the following is a specification.

My invention relates to improvements in lock faces for pin tumbler locks and an object of my invention is to provide a lock face of extremely simple and efficient construction that will fit within a counterbore of figure 8 shape and afford a recess for the reception of a cylindrical head on a key plug.

Other objects are to provide a lock face of this nature embodying two integral lobes having cylindrical peripheries that intersect each other to form a face of substantially figure 8 shape, one of the lobes being thinner than the other and having a relatively large hole therein through which a key plug may be inserted, the head of the key plug seating within the recess formed by the thinner lobe of the face plate and overlapping the ring portion of the thinner lobe of said face plate.

A further object is to provide a lock face in which the only visible parts when the lock is assembled are the line formed by the circular end of the head of the key plug and the line formed by the circular end of the upper lobe of the face plate, the line forming the circumference of the key plug overlapping the line forming the circumference of the upper lobe of the face plate.

Other and more specific objects will be apparent from the following description taken in connection with the accompanying drawings.

In the drawings Figure 1 is an isometric view showing a fragment of a lock housing and showing a lock core withdrawn from said lock housing and said lock core having face plate means constructed in accordance with my invention.

Fig. 2 is a fragmentary sectional view through the face plate, core and housing as they appear when assembled parts being shown in elevation.

Figs. 3 and 4 are detached perspective views of the face plate.

Referring to the drawings, throughout which like reference numerals designate like parts, 5 designates a lock housing having

therein a hole 6 of substantially figure 8 shape that is counterbored at the end as at 7 to afford a shoulder 10.

11 is a lock core, also of figure 8 shape, adapted to fit within the figure 8 shaped hole in the housing 5. The lock core 11 has pin 60 tumbler lock mechanism provided therein and has a movable locking gate 12 controlled by the insertion of a key in the lock and adapted to engage with a shoulder, not shown, in the housing 5 to prevent withdrawal of the core from the housing.

The lock face constituting this invention is in the nature of a flat plate of figure 8 shape arranged to fit snugly within the counterbored portion 7 at the end of the lock 70 housing and rest against the shoulder 10. Said lock face consists of a thicker upper lobe 13 and a thinner lower ring portion 14 having a large hole 15 through which a key plug 16 may be inserted. The ring portion 75 14 is circular and laps over or cuts into the thicker upper lobe 13 and the key plug 16 has a head 17 of larger diameter than said key plug that overlies the ring 14 and is flush with the periphery of the same. 80

The key plug 16 is secured against longitudinal movement in the core housing when assembled and acts as a securing means for the face plate. A lug 18 on the end of the core housing 11 fits into a recess 20 on the 85 inner side of the face plate and prevents the face plate from being turned on the end of the lock core when the lock core is not in the lock housing.

The head of the key plug entirely covers 90 the ring 14 and fits into the counterbore 7 in the housing 5 so that the end of the key plug and the upper lobe 13 which is partially cut away to afford room for the end of the key plug constitute the entire and only visible parts of the lock face when the device is assembled.

The face being of figure 8 shape is reduced to the minimum size and requires only the minimum amount of metal in its 100 construction. This face may be made of very hard metal to resist drilling.

Where circular faces are used I find it desirable to provide faces of several different sizes to conform to the size of the lock in 105 which they are used to satisfy the requirement for locks of artistic appearance. Where this figure 8 shaped face is used I

2
find that it is not necessary to provide faces of different size but that one standard size of face will meet all artistic requirements thereby enabling me to simplify processes of manufacture and reduce the cost of quantity production by standardizing on a single type of lock face.

5 The foregoing description and accompanying drawings clearly disclose a preferred embodiment of my invention, but, it will be understood that this disclosure is merely illustrative and that such changes in the same may be resorted to as are within the scope and spirit of the following claims.

10 15 I claim:

1. In a cylinder lock, a lock face of figure 8 shape having a thicker solid portion at one end and a thinner ring portion at the other end, a key plug arranged to extend 20 through said ring and a head on said key plug arranged to overlap said ring.

2. In a cylinder lock, a lock core, a lock face of figure 8 shape on said core, said lock face having a thicker portion at one 25 end and a thinner ring portion at the other end provided with a hole, a key plug arranged to extend through said hole and a head on said key plug arranged to overlap and cover said ring.

3. In a cylinder lock, a lock housing having a recess of figure 8 shape therein, a lock core adapted to fit into said housing, a lock face of figure 8 shape on said lock core said lock face having a thicker portion at one

end and having a thinner ring portion 35 formed at the other end said ring portion overlapping the circumference of said thicker portion, a key plug arranged to extend through said ring and a head on said key plug arranged to overlap and cover said 40 ring.

4. In a cylinder lock, a lock housing having a recess of figure 8 shape counterbored as its outer end to afford a shoulder, a lock core adapted to fit into said lock housing, a 45 lock face of figure 8 shape on the end of said lock core, said lock face being arranged to fit within the counterbore of said housing and rest against said shoulder one end of said lock face being thinner than the 50 other and having a hole therethrough forming a thinner ring portion and a key plug arranged to extend through said hole and having a head overlapping said ring and flush with the periphery of the ring. 55

5. In a cylinder lock, a lock face embodying two integral lobes having intersecting cylindrical peripheries forming a substantially figure 8 shape one of said lobes being thicker and the other lobe being thinner and 60 overlapping and cutting away said thicker lobe on one side said thinner lobe having a relatively large concentric hole therein and a key plug arranged to pass through said hole and having a larger cylindrical head 65 arranged to overlap the ring portion of said thinner lobe.

FRANK ELLISON BEST.
